CLAIM

I claim the ornamental design for a chest carrier, substantially as shown and described.

DESCRIPTION

FIG. 1 is a front elevation view of an embodiment of the chest carrier of the present invention;

FIG. 2 is a right elevation view of the embodiment of FIG. 1;

FIG. 3 is a left elevation view of the embodiment of FIG. 1;

FIG. 4 is a rear elevation view of the embodiment of FIG. 1;

FIG. 5 is a top view of the embodiment of FIG. 1; and,

FIG. 6 is a bottom view of the embodiment of FIG. 1.

Dotted lines form no part of the claimed invention.
